[57] **CLAIM**

The ornamental design for a dispensing bottle, as shown and described.

DESCRIPTION

FIG. 1 is a front elevational view of a dispensing bottle embodying our new design, the rear elevational view being a mirror image thereof;

FIG. 2 is a view looking from the left side of FIG. 1;

FIG. 3 is a view looking from the right side of FIG. 1;

FIG. 4 is a top plan view of the dispensing bottle; and

FIG. 5 is a bottom plan view of the dispensing bottle.
